ACTUATOR FOR HINGED CLOSURES

John S. Gullborg, Chicago, Ill.

Application June 1, 1937, Serial No. 145,656

2 Claims. (Cl. 268—119)

The present invention relates to actuators for hinged closures. Swinging closures, such as French windows, hatchway covers, screens, ventilator lifts, and like structures usually have actuators for manipulating them so that the closures may be readily and easily moved to adjusted position.

It has been found from experience that sometimes French windows and like closures are so heavy that they become warped, whereupon it is impossible to effect closing tightly enough to exclude rain, snow, sleet and the like. Actuators for such closures are used at the present time, but none is capable of ready adjustment to effect tight closing or sealing when the closures are warped.

An object of the present invention is to provide actuators for hinged closures, which actuators will effect tight sealing or closing when the closures are slightly warped.

Another object of the present invention is to provide an actuator for a hinged closure which, in the main, may be manufactured of stamped parts.

Another object of the present invention is to provide an actuator for the lid of a trailer ventilator, which actuator is economical to manufacture and highly efficient in use.

The above, other and further objects of the present invention will be apparent from the following description and accompanying drawings.

The accompanying drawings illustrate embodiments of the present invention, and the views thereof are as follows:

Figure 1 is a fragmental elevational view of a hinged closure, equipped with an actuator constructed in accordance with the principles of the present invention.

Figure 2 is a fragmental horizontal sectional view taken substantially in the plane indicated by the line II—II of Figure 1.

Figure 3 is a fragmental horizontal sectional view taken substantially in the plane indicated by the line III—III of Figure 1.

Figure 4 is a vertical sectional view through a trailer ventilator equipped with an actuator constructed in accordance with the principles of the present invention.

Figure 5 is a vertical fragmental sectional view, with parts in elevation, taken substantially in the plane indicated by the line V—V of Figure 3.

Figure 6 is a view, partially in horizontal section and partially in plan, taken substantially in the plane indicated by the line VI—VI of Figure 5.

Figure 7 is a view, partially in horizontal section

and partially in plan, taken substantially in the plane indicated by the line VII—VII of Figure 8.

Figure 8 is a vertical sectional view showing a modified construction of certain of the parts.

Figure 9 is a fragmental vertical sectional view, taken substantially in the plane indicated by the line IX—IX of Figure 1.

Figure 10 is a fragmental vertical sectional view, taken substantially in the plane indicated by the line X—X of Figure 1.

Figure 11 is a fragmental vertical sectional view, taken substantially in the plane indicated by the line XI—XI of Figure 4.

The drawings will now be explained.

In Figures 1, 2 and 3, the invention is exemplified in a hinged closure, such as a French window. A frame is indicated at A with the window or sash indicated generally at B. The sash or closure member B is hingedly connected to the frame A by hinges 1 and is adapted to be opened upwardly as viewed in Figures 2 and 3. The sash or closure member B is illustrated as a window carrying a pane or glass C, with top and bottom sash rails 2 and 3 respectively, connected at their ends to stiles 4 and 5.

The actuator illustrated in Figures 1, 2, 3, 5 and 6 includes a stamped plate 6 having a horizontal flange 7 for attachment to the sill of the frame and a vertical flange 8 attachable to the upright member of the frame, by screws or other suitable attaching means. Between the horizontal portion of the plate 6 and the vertical flange 8, and between the side margins of the plate, it is cut away forming an opening 9, in which is rotatably mounted a worm 10. The worm 10 is keyed or otherwise fastened to a sleeve 11 which is of greater length than the worm, projecting from both ends of the worm, as may be observed in Figure 6.

A supplemental plate 12 is fashioned with ears 40 which are bent around the extending end portions of the sleeve 11 to secure the sleeve and worm in position in the plate 6. These portions which are bent around the extremities of the sleeve 11 form bearings 13 for the sleeve and worm. Between the horizontal portion of the plate 6 and the vertical flange 8, the plate is curved downwardly at 14, as shown in Figure 1, to receive portions of the bearings 13 for the sleeve 11. The worm 10 is thus supported in 50 the plate with its axis in horizontal position and closely adjacent the portion of the frame A to which the vertical flange 8 of the plate is attached.

The horizontal portion of the plate 6 is aper- 55

tured at 16, the supplemental plate 12 being apertured to register therewith, for receiving the lower end of a vertical shaft 15 which is supported in the frame A in parallel relationship to the hinge connections of the sash or closure member B to the frame A. A stamped gear 17 having teeth 18 for meshing with the worm 10 is pivoted on the shaft 15. The gear 17 is incomplete as far as its peripheral portion is concerned, and has a tail extension 18a.

A lever 19 is apertured to surround the shaft 15 and rest on top of a portion of the gear 17 and its tail portion 18a. The lever 19 is operatively connected to the tail portion 18a of the gear by means of a screw 20 passing through an aperture in the lever and threaded into the tail 18a, thus connecting together the gear and the lever for oscillating with the shaft. In order to oscillate the shaft 15 in accordance with oscillatory movement imparted to the lever 19, any suitable driving connection may be employed.

The driving connection illustrated consists of two diametrically disposed slots 21 and 22 formed in the lever adjacent the shaft 15, and the shaft 15 is apertured to receive a pin 23 which lies in the slots 21 and 22. The pin 23, in addition to connecting the shaft 15 and lever 19 together for oscillatory movement, supports the shaft in vertical position with respect to the bracket 6. The upper end of the shaft 15 is supported by a stamped bearing including an attaching plate portion 24 and a barrel 25 which receive the upper end of the shaft. For a distance extending downwardly from the upper end of the shaft, the shaft is recessed at 26, to thereby provide a flat surface 27.

Attached to the lower rail 3 of the sash B, is an elongated stamped metal flanged member 28 arranged with its flange 29 parallel to and spaced from the rail 3. This member 28 is secured to the lower rail of the sash by means of screws 30 or other suitable fastening means. Pivoted to the free end of the lever 19 is a shoe 31 having a J-shaped formation to engage the opposite faces of the flange 29 of the member 28 and pass underneath the margin of the flange, as readily observed in Figure 10. The shoe 31 is pivoted to the free end of the lever 19 by means of a pin 32, so that play may occur between the shoe and the lever when the shoe is moved back and forth along the flange 29 to swing the sash or closure member B to adjusted position.

Attached to the upper rail of the sash B is a similar member 33 having a flange 34 extending along and in spaced relation to the rail, as may be observed in Figure 9. This member 33 is secured by screws or like fastening means 35.

Keyed or otherwise fixedly secured to the upper end of the shaft, a slight distance below the barrel 25 of the bearing member, is a crank 36 which projects along the upper rail of the sash for a short distance. An upper lever 37 is apertured at one end as at 38 to surround the shaft 15 and to have movement relatively to the shaft. The lever 37 carries at its free end a shoe 39, pivoted thereto by a pin 40. The shoe 39 has a hooded part 41 which engages over the upper margin of the flange 34 of the member 33 and bears against opposite sides of the flange, as the shoe is moved in use. Means are employed for connecting the crank 36 to the lever 37 in driving relationship.

The means illustrated for accomplishing this purpose comprise upstanding lugs 42 and 43 as

integral portions of the crank which are laterally spaced from the side margins of the lever 37. The lever 37 is provided with upstanding ears 44 and 45 which constitute stops. Threaded into the ears 42 and 43 are screws or bolts 46 and 47, which may be adjusted towards and away from the ears 44 and 45 of the lever to position the lever in desired angular relationship with respect to the crank 36, and also to afford driving connection between the crank and the lever. 10

The sleeve 11 which drives the worm 10 is fashioned with a polygonal interior 11a (Figure 6) to receive the correspondingly shaped end of a removable crank 49. Preferably, the polygonal interior 11a of the sleeve is disposed at the inner end of the sleeve in spaced relationship to the entrance end thereof, to prevent ready insertion of a tool for operating the actuator of the present invention to manipulate the sash from its adjusted position, by an unauthorized person. 20

The sash B is moved to adjusted position with respect to the frame by inserting the crank 49 in the sleeve 11, with the polygonal-shaped end of the crank engaging the interior 11a of the sleeve, whereupon rotation of the crank 49 in clockwise direction, as viewed in Figure 1, will cause the sash B to be swung to opened position, that is, with its free margin swung upwardly, as viewed in Figures 2 and 3. When the sash has been moved to desired position, the crank may be withdrawn, whereupon the sash remains in this position until the crank is again applied and the worm rotated to move the gear 17 in such direction as will move the sash to another adjusted position. 30

It sometimes happens that hinged closures, such as screens, French windows, screen doors and the like, which are manipulated by actuators, warp or sag, which warping is especially noticeable at the upper outer corner of the closure. 40 When such warping occurs, it is well nigh impossible to secure tight sealing between the closure and its frame. The provision of the adjustment between the upper lever 37 and the crank 36 takes care of such warping. 45

Assume that the upper outer corner of the sash B of Figure 1 had warped outwardly so that manipulation of the levers 19 and 37 would not effect tight sealing of the closure against its frame. In this event, the screws or bolts 46 and 50 47 are manipulated as to so angularly adjust the lever with respect to the crank as to draw the upper outer end of the sash tightly against its frame, and thus overcome the effect of the warped condition of the sash. 55

The amount of adjustment of the lever 37 with respect to the crank 36 depends, of course, on the warped condition of the closure, which such adjustment is intended to overcome. The lever 37 and crank 36, in Figure 2, appear with the parts 60 in normal position. If the closure member B is slightly warped, then the screw bolts 46 and 47 would be adjusted to move the left hand end of the lever, as viewed in this figure, a slight distance below that shown in the figure, so that 65 when the closure member is moved against the frame, added pull will be exerted by the shoe which engages the flange 34 of the member 33.

Figures 7 and 8 illustrate a modification wherein the upper lever 37 and the upper member 33 are eliminated, and instead of the utilization of the shaft 15, a pivot pin is employed. In this form of the invention, a stamped metal plate 48 is provided with spaced flanges 49 and 50 for attachment to the sill 51 of a closure frame. 70 75

The central portion of the plate 48 lies above the flanges 49 and 50. The central portion of the plate 48 is apertured at 52 to receive a pivot pin 53, which pin has a head 54, a cylindrical portion 55 to closely fit within the aperture 52, and another cylindrical portion 56 of reduced diameter. This portion of reduced diameter is counterbored and threaded to receive a screw 57.

Surrounding the portion 56 of the pin is a gear 10 formed of two similar stamped sections 58 and 58'. The sections 58 and 58' are separately stamped and then are brought together with their teeth in register and so held, and then centrally bored to form the center opening for the 15 pivot. A horizontally disposed worm 59 is keyed or otherwise secured to a hollow sleeve 60, the ends of which are supported in apertured lugs 61 and 62 turned up from the material of which the plate 48 is made. The worm 59 is in mesh 20 with the gear composed of the sections 58 and 58' and designated generally at E.

A lever 63 of stamped flat metal is apertured to surround the pivot pin 53, surrounding the portion of reduced diameter 56 of the pin. The 25 lever 63 is secured to the gear D by means of rivets, bolts or like attaching means 64 which pass through the lever and sections 58 and 58', thus connecting the gear and lever together for cooperative action.

For covering the worm 59 and sleeve 60, a cover 30 plate of stamped metal 65 has a part overlying the gear D, a part overlying the worm, and a horizontal flange 66 which rests on top of the flange 58 of the plate 48. The cover plate is held in position by screws 67 passing through 35 it and the flange 58 of the plate 48 and entered in the sill 51 of the frame. The screw 57 passes through an aperture in the cover plate and is threaded into the pin 53. The hollow sleeve 60 which carries the worm 59 is provided with a 40 polygonal portion 60' to receive the similarly shaped end of a crank, such as the crank 49, for rotating the worm to actuate the lever 63.

This form of the invention is utilized in connection with a hinged closure, where but one lever is sufficient to operate the closure.

In Figures 4 and 11, there is illustrated an exemplification of the application of an actuator of the present invention to the lift of a trailer 50 ventilator. As usually constructed, trailers are provided with ventilators in their roofs which, when opened, permit circulation of air from the interior of the trailer to the outside. The problem of closing such ventilators, as regards 55 weather conditions, is important. It is necessary to effectively seal such ventilator openings to prevent entry of rain, snow and wind to the interior of the trailer.

In this form of the invention, 68 represents 60 a wall built around the ventilator opening in the roof of a trailer. Hinged at 69 to the wall is a lid or hinged closure 70 adapted to be moved on its hinge to adjusted position. Attached to the underside of the lid or closure 70 is an elongated 65 flanged member 71 having a flange 72 spaced from the lid 70. Secured to the wall 68, by screws 73 or other fastening means, is a flange 74 of a bracket. Outstanding from the flange 74 is a part 75 which is provided with outstanding 70 ears 76 and 77 in which a shaft 78 is rotatably carried. Pinned to the shaft 78 between the ears 76 and 77 is a worm 79.

Supported on a stud 80 carried by the part 75 of the bracket is a stamped gear 81 having a tail piece 82 extending away from the pivot 80

in a direction away from the worm. Movable about the pivot 80 is a lever 83 which is connected to the tail 82 of the gear by means of a rivet 84, thus connecting the lever and gear in operative relationship. Carried at the free end of the lever 83 is a shoe 84 having a part engaging opposite surfaces of the flange 72 of the member 71. The shoe 84 is pivoted to the lever 83 by a suitable pin 85 so that relative rocking movement may occur between the lever and the 10 shoe as the closure member 70 is moved about its hinged connection to the wall 68.

For manipulating the closure member or lid 70, the shaft 78 is provided with a hand wheel 86 disposed near the roof of the trailer and which 15 may be readily manipulated from the interior of the trailer. To open the lid or closure member 70, the hand wheel 86 is turned to the right, whereupon the free end of the lever 83 rises and opens the lid 70 about its hinges. To close, the 20 hand wheel is rotated in the opposite direction, the shoe 84 cooperating with the frame 72 to close the lid against the wall 68.

By reason of the construction illustrated and described, the lid or closure may be tightened 25 against the wall 68 in sealing relation, by giving the hand wheel 86 an additional turn to the left after the closure has been seated, whereupon a squeezing effect takes place between the closure and the wall. If desired, suitable gasket means 30 might be secured to the margin of the wall for engagement by the lid when it is in closed position, as an added means for preventing ingress of rain, snow and sleet.

It will be observed that the actuator of the 35 present invention is one which, in the main, may be manufactured by stampings, as all of the parts, except the worm, the crank and the worm mounting sleeve, may be stamped from suitable metal, thus reducing the cost of manufacture of 40 the actuator. The manner of assembly is simple and can be carried out at minimum expense for labor.

The actuator herein described has proved very 45 efficient in use, and as made is rugged and sturdy to withstand all abuse to which such a device may be put in service. The provision of two levers applied to the top and bottom rails of a large and heavy closure is an advantage because of the fact that the upper lever may be so adjusted as 50 to effect tight sealing of the closure against the frame, should the closure be warped.

The invention has been described herein more or less precisely as to details, yet it is to be understood that the invention is not to be limited 55 thereby, as changes may be made in the arrangement and proportion of parts, and equivalents may be substituted, without departing from the spirit and scope of the invention.

The invention is claimed as follows:

1. In a device of the class described, a frame, a closure hinged to said frame to swing, a bar of angular section attached by a flange to said closure and having a web normal to said closure and another flange parallel to and spaced from the closure, a slide formed of sheet metal shaped to provide a U-head to fit about said other flange in longitudinal sliding relation, said slide having a part lying in the plane of said web, an operating arm pivoted at one end to said slide part 70 with a portion of the arm lapping said web, a stamped gear connected to the other end of said arm in driving relation, a hollow worm supported in mesh with said gear, a hollow bearing sleeve 75 for supporting said web with its ends projecting

beyond the ends of the worm, journals supporting said sleeve ends, the interior of said sleeve being of polygonal cross section, and a removable crank having a part of polygonal section to conform to the interior of said sleeve enterable therein for rotating said worm to actuate said closure.

2. An actuator for a hinged closure member, including a shaft along said member adjacent its hinges, gear means for oscillating said shaft, an elongated flanged member secured to said closure with its length at right angles to the hinge,

an arm pivoted at one end to said shaft and at its other end carrying a shoe for slidably engaging the flange of said member, a crank fastened to said shaft in driving relation and extending in the direction of the length of said arm, said crank having right angled ears adjacent and spaced from the margins of said arm, and bolts threaded in said ears and movable endwise towards and away from said arm for adjusting the relative angular relationship of said arm and crank. 5

JOHN S. GULLBORG.
